US0D1065994S

(12) **United States Design Patent** (10) **Patent No.:** **US D1,065,994 S**
(45) **Date of Patent:** **** Mar. 11, 2025**

(54) **TOOL RETAINER**

(71) Applicant: **Kennametal Inc.**, Latrobe, PA (US)

(72) Inventors: **Arkadiusz Dlugosz**, Zory (PL); **James R. Geyer**, Manns Choice, PA (US)

(73) Assignee: **KENNAMETAL INC.**, Latrobe, PA (US)

(**) Term: **15 Years**

(21) Appl. No.: **29/865,532**

(22) Filed: **Jul. 29, 2022**

(51) LOC (15) Cl. **15-04**

(52) U.S. Cl.

USPC **D15/21**

(58) **Field of Classification Search**

USPC D15/21

CPC E21C 35/197; F16D 1/0835

See application file for complete search history.

(57) **CLAIM**

The ornamental design for a tool retainer, as shown and described.

DESCRIPTION

FIG. 1 is a top view of the tool retainer;

FIG. 2 is a perspective view thereof;

FIG. 3 is a perspective view thereof;

FIG. 4 is a front side view thereof;

FIG. 5 is a left side view thereof;

FIG. 6 is a rear side view thereof;

FIG. 7 is a right side view thereof;

FIG. 8 is a perspective view thereof; and,

FIG. 9 is a perspective view thereof.
